UNITED STATES PATENT OFFICE.

WALTER L. COLLINS, OF MILFORD, MASSACHUSETTS.

BUILDING-WALL.

1,240,121.

Specification of Letters Patent. Patented Sept. 11, 1917.

Original application filed August 1, 1910, Serial No. 574,768. Divided and this application filed January 8, 1913. Serial No. 740,814.

To all whom it may concern:

Be it known that I, WALTER L. COLLINS,
a citizen of the United States, residing at
Milford, in the county of Worcester and
5 State of Massachusetts, have invented an
Improvement in Building-Walls, of which
the following is a specification.

This application is a division of my application #574,768, filed August 1, 1910, for which Letters Patent have been granted #1,067,469, dated July 15, 1913.

This invention relates to building construction and more particularly to the construction of a building wall adjoining a window, whereby a caseless window is provided having the usual window-weights, and its weight-compartments are effectively sealed at the inside of the building.

In carrying out this invention the usual window-frame has grounds attached to the outside of its opposite sides and top, although said grounds may be made separate, if desired, and said grounds are arranged at the inside of the weight-compartments and form inside walls therefor, and said grounds are also arranged flush with the studs adjoining the window-frame, so that the lath and plaster wall instead of terminating, as usual, at a point adjacent the weight-compartments, will extend over the grounds which form the inside wall of said compartment and also over the edge of the window-frame, terminating at the window-stop, and a metallic reinforcement is embedded in the lath and plaster wall, at the edge adjoining the window-stop, which is attached at its inner edge to the aforesaid grounds and extends across the plaster wall from back to front, and its outer edge is arranged at the corner of the wall and is exposed.

The window-stop is attached to the window-frame and extends from the sash to the exposed portion of the metallic corner reinforcement.

45 By my invention the usual inside casing or trim is omitted, yet the corner of the lath and plaster wall is protected and the weight-compartments are effectively sealed at the inside of the building, so that no draft passes lead from said compartments into the room.

In further carrying out my invention the window-frame is set in the building wall to leave a space beneath its sill, and the stool 55 is arranged on said sill, but the usual apron

beneath the stool is omitted, and in lieu thereof the lath and plaster wall is extended across the space beneath the sill, and over the end of the sill up to the stool, and a metallic reinforcement is arranged at the top 60 of said wall, consisting of a strip of sheet metal bent at right angles to form an attaching-portion which is attached to the sill and the stop-portion which is extended over the top of the wall, directly beneath the 65 stool.

Figure 1 is a front elevation of a portion of an exterior building wall embodying this invention, having a window.

Fig. 2 is an enlarged horizontal section of a portion of the window-frame adjoining the wall taken on the dotted line 2-2, Fig. 1.

Fig. 3 is an enlarged vertical section of the window-frame and adjoining wall, broken to save space on the drawing, and taken on the dotted line 3-3, Fig. 1.

The window-frame 10 and its casing 12 are of usual construction. 13 is a ground which is or may be attached to the outside of the frame 10, at its inner edge, thus forming weight - compartments between said grounds and the casing 12, said grounds serving as the inside walls of said compartments. 15 is the usual stud arranged adjacent the opening provided for the window-frame, and which usually forms one side wall of the weight - compartments. The ground 13 is arranged flush with the stud 15 and with the inner edge of the window-frame, as represented in Fig. 2. The lath and plaster wall 16 is carried over the ground 13 and the inner edge of the window-frame, thereby effectively sealing the weight - compartments, and said lath and plaster wall terminates at the inner side or 20 25 30 35 40 45 50 55 60 65 70 75 80 85 90 95

plaster wall terminates at the inner side of the window-frame, so that the usual window-stop 17 which is attached to said frame will extend over and in contact with the edge of said wall. The inner edge of said window-stop terminates a short distance inside of the exposed side of the lath and plaster wall, leaving the corner of said wall exposed and unprotected, and, herein, a metallic reinforcement 25 of any suitable form is embedded in the lath and plaster wall, and extends diagonally across said wall from back to front, its inner edge being attached to the ground 13 by nails or other means and its outer edge being disposed at the corner of the wall and is exposed. The 110

inner edge of the window-stop terminates at the exposed portion of the metallic reinforcement.

30 represents the usual window-sill and 5 31 the stool arranged on said sill, and to avoid the necessity of providing an apron beneath said stool, as has usually been the case, the lath and plaster wall is continued upward as at 32 across the space beneath the 10 window-sill and over the inner end of said sill and terminates at the under side of the stool, and at its upper edge a metallic reinforcement is provided, particularly for forming a stop for the plaster wall. Said 15 reinforcement may consist of a piece of sheet metal bent intermediate its width at a right angle or thereabout, and said reinforcement is arranged with one portion 35 in contact with the sill and its other portion 36 extended forward at the top of the sill, and in contact with the under side of the stool and said portion 35 is attached to the sill by 20 nails or otherwise, preparatory to forming the plaster-wall. By this construction the 25 usual space beneath the sill is effectively closed and the usual apron omitted. The expression lath and plaster wall is herein used as denoting an ordinary form or kind of wall and in lieu thereof any other well-known form or kind of wall may be employed.

The several features of my invention are all involved in the caseless window here shown, but it is obvious that they may be 35 separately employed in divers ways, and that some of them are also applicable to doors where it is desired that the plaster wall shall extend to and flush with the edge of the frame, thereby to serve as a substitute 40 for the usual casing or trim.

I claim:—

1. A building-wall having an opening, a window frame arranged therein having compartments for the window weights, the 45 grounds forming the inner boundary of the compartments being arranged flush with the inner surface edge of the frame, window stops arranged on and in contact with the face of the frame, said stops projecting inwardly beyond the inner edge of the frame to provide with such inner edge angularly

related surfaces having a depth transverse the frame substantially equal to the thickness of the plaster wall, the meeting line of the inner edge of the frame and the relatively inner projecting face of the stops forming a limit for the forward edge of a plaster wall, whereby the stops overlie the edge of the plaster wall to serve as a substitute for the usual casing. 55

2. A building wall having an opening, a window-frame set therein having compartments for the window-weights, the grounds at the inside of said compartments being arranged flush with the inner edge of the frame, window-stops arranged on the face of the frame which project inward therefrom, a plaster wall extended over the grounds and the inner edge of the frame which abuts against the projecting portion of the stops and a metallic reinforcement embedded in the wall at its edge, one edge of which reinforcement rests against the edge of the projecting portion of the stop and is exposed at 60 such point. 70

3. A building wall having an opening, a window-frame set therein, having compartments for the window-weights, grounds arranged at the inside of said compartments flush with the inner edge of the window-frame, a plaster wall extended over said grounds, and the inner edge of the window-frame, which terminates flush with the face of the frame, and a metallic reinforcement embedded in said plaster wall and extended diagonally across the same from back to 80 front, one edge of which is attached to said grounds and the other edge of which is exposed at the inner corner of the plaster wall, and a window stop arranged on the face of the frame which is extended inward over the edge of said plaster wall, and terminates at 85 the exposed portion of the metallic reinforcement. 90

In testimony whereof, I have signed my 95 name to this specification, in the presence of two subscribing witnesses.

WALTER L. COLLINS.
